H. M. BODINE,
RAILWAY TIE,
APPLICATION FILED NOV. 23, 1916.

1,237,863.

Patented Aug. 21, 1917.

Henry M. Bodine INVENTOR.

BY

Castor A. Latham ATTORNEY

UNITED STATES PATENT OFFICE.

HENRY M. BODINE, OF WICHITA, KANSAS, ASSIGNOR OF ONE-HALF TO EDWIN C. BLANCHARD, OF WICHITA, KANSAS.

RAILWAY-TIE.

1,237,863.

Specification of Letters Patent. Patented Aug. 21, 1917.

Application filed November 23, 1916. Serial No. 133,035.

To all whom it may concern:

Be it known that I, HENRY M. BODINE, a citizen of the United States, residing at Wichita, in the county of Sedgwick and State of Kansas, have invented a new and useful Railway-Tie, of which the following is a specification.

My invention relates to new and useful improvements in railway ties and more particularly to metallic ties and means for securing the rails in place upon the ties, and the object of my invention is to provide a tie that will pack the ballast of the road-bed, and one from which the rails can be quickly removed and replaced with new rails without the use of spikes. The further object is to provide a tie that will firmly hold the rail in place and have the resiliency of a wood tie, and the still further object is to provide a tie on which the rails can not spread.

I attain the objects of my invention in constructing a railway-tie in the manner illustrated by the drawings hereto attached, in which like letters indicate like parts.

Figure 1, is a side elevational view of the tie, partly broken away. Fig. 2 is a cross section of the tie on the out-side of the rail and a side view of a rail. Fig. 3 is a longitudinal view of tie and rail clamps showing insulation. Fig. 4 is a perspective of a removable clamp. Fig. 5 is a perspective of a section of a railway, with my improved tie.

In Fig. 1 A is the tie with a part broken away indicating the stationary rail clamp B and the removable railway clamp C, the T-rail G and the fastening by which the rail is secured to the tie, B, C, D, and E. B is made integral with the tie and is on the outer end of the tie, outside the rail. C is a removable rail clamp with a lip D passing through the slot F and is bolted down to the tie by bolt E which may be tapped into the tie or come from the tie up with a nut on the top of the clamp. The tie A is hollow and may be reinforced by concrete.

In Fig. 2 A is a hollow rail-road tie with a flat bearing surface for a T-rail; while the under side of the tie has a narrow margin along each side of the tie that slants up toward the center of the tie, and the remainder or center of the bottom side of the tie slants to a point on a line with the center of the tie; as indicated by H, H, and

I, I, in this figure. G is the T-rail, and dotted line C indicates the removable clamp, and E indicates the bolt that secures the removable rail-clamp to the tie.

In Fig. 3 A is the tie, G is the rail, B is 60 the stationary clamp and C the removable clamp that secures the rail to the tie. J is the insulation between the rail, clamps, and tie, to prevent the grounding of the electric current in the rail.

I am aware that rail-way ties have been in use that have a projecting under-side, but none of them have the form on the und. side of the tie that will secure its position in the ballast without loosening or spreading the 70 ballast, which I claim for this tie. The stationary clamps on the outer side of each rail will prevent the rails from spreading; while the removable rail-clamp on the inner side of the rails may be quickly removed or 75 secured in place holding the rail secure against the stationary rail-clamp, thereby saving time and labor.

Having thus described my invention what I claim as new and desire to secure by Letters Patent is:

1. A hollow railway-tie, with one side having a straight rail surface with a means for securing and preventing the railway-rails from spreading; two rectangular parallel side-walls; the base-walls flared out to a line parallel with the center of the tie, each of said base-walls having a triangular groove parallel to and near the side-walls, extending from end to end, of said tie, the 90 ends of said tie being open, substantially as shown and described.

2. A hollow railway-tie with open ends, having the upper side or wall provided with means for securing and preventing the 95 spreading, of the railway-rails, two rectangular side-walls of equal width and parallel to a line in the center of the tie; the under side or base-walls of said tie converging downward to a line parallel to the 100 middle vertical plane of the tie; said base-walls each provided with a groove adjacent and parallel to the side-walls of the tie, substantially as shown and described.

3. A hollow railway-tie with open ends, 105 with one side, provided with the means for securing the railway-rails; the opposite side or base, consisting of two downwardly converging base-walls; each base-wall provided with a groove, parallel with and near 110

the upper side of the base-wall, on the exterior surface of the tie, substantially as shown and described.

4. A hollow railway-tie, provided with 5 open ends, an upper side-wall provided with the means for securing and preventing the spreading of the railway-rails, two vertical,

and parallel rectangular side-walls, and a base-wall with downwardly converging sides provided with a groove on each side 10 parallel with the side-wall of the tie, substantially as shown and described.

HENRY M. BODINE.
